US0D1109553S

(12) **United States Design Patent** (10) **Patent No.:** **US D1,109,553 S**
(45) **Date of Patent:** **** Jan. 20, 2026**

(54) **BLANKET**

(71) Applicant: **Nu-nique Ltd**, Kent (GB)

(72) Inventor: **Sandra Shirras**, Kent (GB)

(73) Assignee: **NU-NIQUE LTD**, Kent (GB)

(**) Term: **15 Years**

(21) Appl. No.: **35/523,212**

(22) Filed: **Oct. 24, 2024**

(80) **Hague Agreement Data**

Int. Filing Date: **Oct. 24, 2024**

Int. Reg. No.: **DM/242279**

Int. Reg. Date: **Oct. 24, 2024**

Int. Reg. Pub. Date: **Dec. 6, 2024**

(30) **Foreign Application Priority Data**

May 14, 2024 (GB) 6365868
May 14, 2024 (GB) 6365869
May 14, 2024 (GB) 6365870

(51) **LOC (15) Cl.** **06-13**

(52) **U.S. Cl.**

USPC **D6/603**

(58) **Field of Classification Search**

USPC D6/595, 596, 597, 602, 603, 605, 608,
